UNITED STATES PATENT OFFICE

110,494

DESIGN FOR A PRINTED FABRIC

Shigeo Oshima, Honolulu, Territory of Hawaii,
assignor to Fujii Junichi Shoten, Ltd., Honolulu, Territory of Hawaii, a corporation of the Territory of Hawaii

Application May 6, 1938, Serial No. 77,044

Term of patent 7 years

To whom it may concern:

Be it known that I, Shigeo Oshima, a subject of the Empire of Japan and resident of Honolulu,
city and county of Honolulu, Territory of Hawaii, have invented a new, original, and ornamental Design for Printed Fabric, of which the following is a specification, reference being had to the accompanying drawing, forming a part thereof, and in which drawing the fabric is shown in plan.

I claim:

The ornamental design for printed fabric, substantially as shown.

SHIGEO OSHIMA.
